UNITED STATES PATENT OFFICE.

GEORGE HENRY GILLINGHAM, OF KENTVILLE, NOVA SCOTIA, CANADA.

CAR-DOOR.

1,216,436.

Specification of Letters Patent. Patented Feb. 20, 1917.

Application filed March 23, 1916. Serial No. 86,296.

To all whom it may concern:

Be it known that I, GEORGE HENRY GILLINGHAM, a subject of the King of Great Britain, and resident of Kentville, in the 5 Province of Nova Scotia, Dominion of Canada, have invented certain new and useful Improvements in Car-Doors, of which the following is the specification.

This invention relates to improvements in 10 railway car doors and the objects of my invention are to render the door wind and water tight so that merchandise shipped in the car is not liable to suffer in consequence of the weather, to obviate any liability of 15 the door becoming displaced due to jarring in the train, to simplify the construction and to permit of the door being readily actuated with a minimum of labor and loss of time.

20 With the above and other objects in view the invention consists essentially of the improved construction particularly described and set forth in the following specification and accompanying drawings forming part 25 of the same.

In the drawings,

Figure 1 is a fragmentary side elevation of a railway car embodying the present invention.

30 Fig. 2 is a transverse section through Fig. 1.

Fig. 3 is a sectional perspective view of the locking device.

35 Fig. 4 is a perspective of the latch of the locking device.

Fig. 5 is a perspective view of the door lever.

Like characters of reference refer to like parts in the several figures.

40 Referring to the drawings, A represents a railway car provided with the usual doorway 10 in the side thereof having its upper and lower edges 11 and 12 beveled downwardly and substantially parallel.

45 It will be seen that the upper beveled edge 11 terminates in a substantial shoulder 13 designed to engage with the inner upper edge of the door 14 locking the same in position and preventing any liability of its 50 excessive displacement inwardly, while the lower edge of the door may be provided with a felt or like resilient strip 15 adapted to intimately engage with the lower beveled edge 12 of the doorway and render the door 55 when in a locked position wind and water tight.

The door 14 is secured to the lower end 16 of a combination hinge provided intermediate of its length with a connecting link 17 pivotally connecting the upper and lower 60 ends 18 and 16 together, the former of which is provided with an overhanging guard 19 housing the roller 20 rotatably mounted therein.

The roller 20 is designed to engage with 65 the longitudinally extending beam 21 which is of substantially Z-shape in cross section, having one of its flanges operatively secured by bolts or the like to the side of the car A, the other flange being downwardly disposed 70 to engage with the distance piece 22 carried by the upper portion 18 of the hinge and located between the same and the side of the car.

The door is further provided on its outer 75 face and intermediate of its height with an automatic locking device 23 comprising the casing 24 secured by bolts or the like to the door 14 and provided with a slot 25 through the center thereof slidably engaging the 80 latch 26 which is provided with a slot 27 coaxing with the pin 28 extending transversely across the said casing and adapted to prevent undue displacement of the said latch member. 85

The lower outer edge 29 of the latch is substantially curvilinear and is provided with an orifice 30 therethrough, the object of which will be made clear hereafter.

The door lever 31 is of substantial U- 90 shape, having the free ends of the parallel arms provided with offsets 32 rotatably engaging the eye bolts 33 which pass through the sill 34 of the car, the said lever having a shank 35 provided intermediate of its ends 95 with an offset portion 36 designed to form a hand grip or step.

An orifice 37 extends through the end of the shank and is adapted to slidably engage with the casing 24 of the locking device, and 100 is further provided adjacent to one of its edges with a projection 38 having an orifice 39 therethrough adapted to register with the orifice 30 in the latch member 26 when the lever is in closed engagement with the door thereby facilitating in passing a wire or the like through the said orifices and sealing the same to prevent tampering with the mechanism carried by the car. 105

The parallel arms 31 of the door lever 110 are provided intermediate of their ends with angularly disposed projections 40 adapted

to engage with the lower edge of the door 14 facilitating in elevating the same, and locking it in position, or in releasing it when the door is about to be opened.

5 The assembly of the device will be readily understood from the foregoing description.

When a car fitted with this type of door is in use it is only necessary to rotate the lever 31 upwardly about its offset ends 32 during 10 which operation the projections 40 engage with the lower edge of the door 14 elevating the same so that the upper edge of the door is engaged with the beveled portion 11 of the doorway 10. The door is now pushed

15 into place by closing the lever 31 against the outer face of the same and the casing 24 of the locking device passes through the orifice 37 in the shank 35 and the latch 26 is automatically actuated to engage the lever and secure it in closed position.

A wire is now passed through the orifices 29 and 30 and a seal is attached to the ends thereof. In opening the door the seal is broken and the latch 26 manually elevated 25 when the lever 31 is rotated downwardly, resulting in the door assuming the position shown by the dotted lines in Fig. 2; hanging directly vertically under the roller 20 so that the slightest effort of the train man 30 will displace the door endwise giving access to the car. When the door is open the off-

set portion 36 of the shank 35 is capable of being used as a sill step to facilitate entry into the car.

As many changes could be made in the 35 above construction and many apparently widely different embodiments of my invention, within the scope of the claim, constructed without departing from the spirit or scope thereof, it is intended that all matter contained in the accompanying specification and drawings shall be interpreted as 40 illustrative and not in a limiting sense.

What I claim as my invention is:

A railway car including door closing 45 means including a lever having a shank, a tapered head on the shank, a U shaped extension on said shank, angular projections on the legs of the U shaped portion, in-turned lateral extensions on the ends of said 50 legs, and straps on the car for pivotally holding said lateral extensions, said means adapted to close the car door when in upright position and to serve as a step when in downward position. 55

In witness whereof I have hereunto set my hand in the presence of two witnesses.

GEORGE HENRY GILLINGHAM.
